UNITED STATES PATENT OFFICE.

THOMAS HILL, OF QUINCY, ILLINOIS, ASSIGNOR TO THE ELECTRIC WHEEL COMPANY, OF SAME PLACE.

MACHINE FOR HEADING SPOKES.

SPECIFICATION forming part of Letters Patent No. 470,566, dated March 8, 1892.

Application filed November 22, 1890. Serial No. 372,344. (No model.)

To all whom it may concern:

Be it known that I, THOMAS HILL, of Quincy, in the county of Adams and State of Illinois, have invented a certain new and useful Improvement in Electric Machines for Making Metal Wheels, &c., of which the following is a full, clear, and exact description, reference being had to the accompanying drawings, forming part of this specification.

10 My invention relates to an improved electric machine for securing the spokes to the rims of wheels or pulleys; and my invention consists in features of novelty hereinafter fully described, and pointed out in the claims.

15 Figure I is a side elevation of my improved machine. Fig. II is a rear end view or elevation. Fig. III is a horizontal section taken on line III III, Fig. I. Fig. IV is an enlarged detail view of the inner end of one of the 20 rim-moving levers, part in section. Fig. V is an enlarged vertical section of the spoke contact-plates, taken on line V V, Fig. I. Figs. VI and VII are diagrams illustrating the manner of forming the heads or shoulders on 25 the spokes. Fig. VIII is a vertical section through the sliding block, &c.

Referring to the drawings, 1 represents a base or bed plate to which the other parts are secured or upon which the other parts are 30 formed.

2 represents a head having an upwardly-extending arm 3, provided with a threaded socket through which passes a threaded rod or shaft 4, made hollow at its lower end to receive the stem 5 of an upper contact-plate 6.

35 7 represents a lever fitting in the slotted upper end of the rod or shaft 4 and pivoted thereto at 8. The lever is provided with a cam-head 9, which bears upon the upper end 40 of the stem 5, as shown clearly by dotted lines, Fig. I. The stem 5 is capable of vertical movement within the hollow shaft 4, thus permitting the contact-plate 6 to be raised or lowered, and the plate is guided in this move-

45 ment by a slide 10, secured thereto and fitting between lugs or ears 11 on the arm 3, with which it has a dovetail connection. Beneath the contact-plate 6 is a plate 12. (See Figs. I and V.) These plates are preferably 50 provided with removable pieces 13, having

semicircular grooves, as shown in Fig. V, to receive the spokes 14 of the wheel or pulley. The upper piece 13 should be insulated from its plate 6. To the lower plate 12 is connected one of the wires 15 of an electric circuit. 55

In the head 2 there is journaled a shaft 16, provided with an operating-lever 17.

18 represents a sliding block fitting in an opening in the head 2, and against the rear end of which a cam 19 on the shaft 16 bears. 60 There should be an insulated contact between the cam and the sliding block, as shown at 20, Fig. I, and the block should be insulated from the head 2.

21 represents the other wire of the circuit, 65 which is connected to the plate 18.

22 represents cams on the shaft 16 and which operate upon the outer ends of levers 23, pivoted at 24 to a sliding block 40, fitting in the opening in the head 2 in front of the block 18. 70 The levers 23 have upwardly-extending ends 25, which are adapted to come in contact with the rim 26 of the wheel when the outer ends of the levers 23 are depressed by the cams 22. The ends 25 of the levers should have an insulated bearing with the rim 26. 75

41 represents a rod which passes through the block 18 and is made fast at its inner end in the block 40. (See Fig. VIII.) The blocks are recessed at 42 to receive a spring 43, which 80 surrounds the rod 41 to keep the blocks 18 and 40 apart when in their normal positions.

44 is a spring on the rod outside of the block 18. The inner end of this spring bears against a plate or cross-strip 45, secured to the head 85 2 so as not to be movable. The outer end of the spring 44 bears against a washer 46, preferably recessed, as shown, beyond which is a nut 47 on the rod.

The operation of my machine is as follows: 90 The outer ends of the spokes are first inserted within the sockets or perforations of the rim 26, either before or after they are secured to the hub of the wheel, preferably after. The wheel is then turned to bring the spokes over 95 the lower contact-plate 12. The upper contact-plate 6 is then lowered first by a forward and downward movement of the lever 7 in the direction of the arrow, Fig. I, which causes the cam 9 to bear against the upper end of the 100

stem 5 of the plate and move the plate downwardly, and, secondly, by turning the lever in a horizontal direction, which revolves the threaded shaft 4 within the threaded socket 5 of the arm 3 so as to make a close contact between the plate 6 and the spoke 14. The next step is to move the lever 17 in the direction of the arrow, the first part of the movement of which causes the cams 22 to depress the 10 outer ends of the levers 23 to automatically set the rim 26 radially away from the center of the wheel, and the continued movement of the lever 17 brings the cam 19 against the sliding block 18 and forces the inner end of the 15 sliding block against the outer end of the spoke, thus establishing the electric circuit between the wires. The continued movement of the lever holds the rim in its outer position (for, as will be seen, the cams 22 have 20 lower ends formed in the arc of circles drawn through the center of the shaft) and also causes the forming-block 18 to be pressed in farther to produce the head 30 on the outer end of the spoke, as shown in Fig. VI, the current of electricity, having heated the spoke, 25 permitting this head to be formed. Just as the head is formed the inner end of the block 18, compressing the spring 43, comes against the outer end of the block 40, and the two 30 blocks and the levers 23 will then move forward together until the washer 46 comes against the piece 45, causing a shoulder 31 to be formed on the spoke inside of the rim, as shown in Fig. VII, and the rim having been 35 set outward while the head was being formed and then permitted to move inward as the inner shoulder is formed the result is that when a wheel is completed the rim is concentric with the hub and a perfect wheel is produced. 40 When the cam 19 leaves the head 18, the spring 44 pulls the heads 18 and 40 back to their normal position, the spring 43 separating the blocks. This completes the attachment of the spoke to the rim and the next 45 operation is to unscrew the sleeve or shaft 4 and raise the lever 7, permitting the plate 6 to be raised by a spring 6^a, connecting it to the arm 3, and the wheel is then turned to bring the next spoke into position to be attached to the rim, and thus the operation 50 goes on continuously until all of the spokes have been united to the rim.

It will be seen that by adjusting the nut 47

the amount of metal consumed in making the head on the spoke will be regulated. 55

With a machine thus arranged for securing the spokes to the rim of a wheel by electric heating, permitting the heads and shoulders to be formed, a wheel can be quickly produced with a secure joint between the spokes and 60 the rim.

I do not want to be limited to any particular location of the insulators of the different parts, nor do I want to be limited to any particular manner of applying the wires 15 and 65 21 to their respective parts, or to any other such mere matters of detail, which do not change or affect the operation of my machine.

I claim as my invention—

1. In an electric machine for securing the 70 spokes to the rim of metal wheels, &c., the combination of the lower contact-plate, an upper contact-plate, and means for moving the upper plate, consisting of a hollow threaded shaft supported in a threaded bearing and receiving 75 a stem on the upper end of the plate and a lever pivoted to said shaft and having a cam bearing on the upper end of said stem, substantially as and for the purpose set forth.

2. In an electric machine for securing the 80 spokes to the rim of a metal wheel, in combination with contact-plates, a sliding head, pivoted levers for setting the rim, and a shaft having a lever and cams for moving said head and pivoted levers, substantially as and for 85 the purpose set forth.

3. In an electric machine for securing the spokes to the rim of metal wheels, the combination of sliding heads, rod 41, springs 44 and 43, sliding blocks and levers pivoted to one 90 of the sliding blocks, and means for moving the blocks and levers, substantially as and for the purpose set forth.

4. In an electric machine for securing the 95 spokes to the rim of metal wheels, the combination of sliding heads 18 and 40, a cam for moving the heads, levers pivoted to one of the heads, cams for moving the levers, rod 41, springs 43 and 44, cross-piece 45, washer 46, and nut 47, substantially as and for the purpose set forth. 100

THOMAS HILL.

In presence of—

CHAS. G. COMSTOCK,
ERNEST A. HENDERSON.
